UNITED STATES PATENT OFFICE.

ANDREW JACKSON GRUSH AND JOHN BENTON SIMMONS CASE, OF
DEFIANCE, IOWA.

SOOT-ACCUMULATOR.

SPECIFICATION forming part of Letters Patent No. 340,113, dated April 20, 1886.

Application filed January 28, 1885. Serial No. 154,075. (No model.)

To all whom it may concern:

Be it known that we, ANDREW JACKSON GRUSH and JOHN BENTON SIMMONS CASE, citizens of the United States, residing at Defiance, in the county of Shelby and State of Iowa, have invented certain new and useful improvements in soot-accumulators for the purpose of accumulating the soot in stove-pipes and other smoke-pipes and removing the same therefrom, of which invention the following is a full, clear, and exact description, reference being had to the accompanying drawing, and to letters of reference marked thereon, making a part of this specification.

Our invention consists of a certain novel construction of soot-accumulators for stove-pipes and other smoke-pipes, which will be fully understood from the following description and claim.

The accompanying drawing represents a side view of a part of a stove-pipe with our soot-accumulator attached thereto, said pipe having both a vertical and a horizontal portion therein, and each portion having a soot-discharge or cap for removing the accumulated soot.

The two vertical portions A A' of the smoke-pipe are connected by means of an elbow, C, and the upper part has a dependent pocket, B', provided with a removable cap, B, through

35 pocket, which interrupts the current of smoke by producing a lull or eddy therein, and thus allows the particles of soot to fall, instead of being carried forward by the draft.

The horizontal portion D of the smoke-pipe is made with a pocket, B', provided with a removable cap at the bottom of said pocket, as shown in the drawing; also this horizontal portion of the smoke-pipe has a scraper, E, 40 the handle of which projects through a hole, F, provided with a slide, G, by means of which said hole may be opened and closed at pleasure. By means of this scraper the soot lodged in the lower part of this pipe D may 45 be scraped into the upper pocket, B', and then removed therefrom, as already mentioned, by removing the cap from said pocket.

Having thus described our invention, what we claim, and desire to secure by Letters Patent of the United States, is—

In a soot-accumulator, the combination of the pipe D, having a pocket, B', provided with a removable cap, scraper E, and slide G, all arranged to operate substantially as set 55 forth.

ANDREW JACKSON GRUSH.
JOHN BENTON SIMMONS CASE.
